Primary Examiner—Ian Simmons*Assistant Examiner*—Charles D Hanson(74) *Attorney, Agent, or Firm*—David R. McKinney(57) **CLAIM**

The ornamental design for a disc storage system, as shown and described.

DESCRIPTION

FIG. 1 is a perspective view of a disc storage system in an open position showing our new design;

FIG. 2 is a perspective view thereof, in the closed position, with the indexing tab removed;

FIG. 3 is a top view thereof;

FIG. 4 is a front view thereof;

FIG. 5 is a bottom view thereof;

FIG. 6 is a side view thereof, the opposite side being a mirror image; and,

FIG. 7 is a back view thereof.
